(57) **CLAIM**

The ornamental design for a gravimetric measuring instrument of capsule for pharmaceutical purposes, as shown and described.

DESCRIPTION

FIG. 1 is a front and right side perspective view of a gravimetric measuring instrument of capsule for pharmaceutical purposes showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines are included for illustrative purposes and form no part of the claimed design.
